UNITED STATES PATENT OFFICE.

CHARLES E. WICKERSHAM, OF JOHNSTOWN, PENNSYLVANIA.

RESILIENT STRIKER PLATE AND COUPLER CARRIER.

Application filed August 2, 1924. Serial No. 729,707.

One of the great items of losses in freight car upkeep experienced by railroad companies is that due to repairs arising from breaking of the striker plates commonly used to limit the inward movement of the coupler. By reason of the constant hammering of the coupling heads the plates are short lived and the plates of each car break repeatedly, which in each instance throws the shock directly on the frame of the car, on the coils of the coupler springs, the inner ends of the bars, the coupler housing and also the car beams that form the coupler support. Thus the breaking of the striker plate results in the breaking down of the whole of the associated car connecting parts of the freight car. Unless inspection occurs promptly and the car is side-tracked or sent to the shop for repair the loss and damage that may be done is measured only in wrecks and loss of life. Usually it means the reconstruction of the ends of the car and particularly the car parts. The striker plates are so located as to allow a certain amount of resilient play of the coupler heads, but when the pressure becomes too great for the coupler springs, the coupler head strikes the striker plate which is designed to take the shock. The striker plates by reason of this constant hammering break and the shocks are received by the vital parts of the car construction. By my invention I have provided a resilient striker plate having springs so designed that the coupler has the same play as in the ordinary car construction, but the plate is held by springs designed to withstand all possible pressure that may occur at this point, that is, so as to have a large safety factor. Moreover, they are designed to coact with the springs of the coupler to raise within a very narrow margin of movement within a safe limit of movement of the coupler, a counter pressure that will prevent the jamming of the coupler parts and absorb the shock of the ramming of the cars.

The invention also provides a convenient support for the coupler wherein the wear on the coupler due to its longitudinal and swinging movement is largely overcome and wherein any wear that may occur is corrected.

The invention may be contained in car couplers and striker parts that may be varied and still be within the purview of the novelty of my invention. In order that a

practical application of my invention may be described I have selected two or three forms of the resilient striker plate assemblies as examples of structures containing my invention and shall describe them in detail. The said resilient striker plates and the coupler are shown in the drawings.

Figure 1 is a perspective view of a resilient striker plate assembly of one form and of a coupler head. Fig. 2 is a top broken view of a buffer member or part of the striker plate assembly. Fig. 3 is a transverse sectional and broken view of the resilient striker plate assembly and coupler. Fig. 4 is a longitudinal sectional and broken view of the resilient striker plate assembly. Fig. 5 is a top view of a resilient striker plate assembly having a larger number of springs than that shown in Figs. 1 to 4, inclusive.

In the form of construction illustrated in Figs. 1, 2, 3 and 4, the resilient striker plate assembly comprises two telescoping members. One is a buffer member consisting of a shank 6 and a head or striker plate proper 14 and the other is a supporting member which includes a housing 7 in which the buffer shank 6 is slidably supported. The buffer shank 6 is provided with a plurality of longitudinally extending pockets 8 which are open at the inner end of the shank and in which springs 9 are located. The springs 9 protrude from the ends of the pockets so as to press against the inner end of the housing 7. The pockets 8 are separated by a relatively thick partition wall 10 having one or more vertical slots 11 that extend parallel to the sides of the wall and are elongated lengthwise of the wall, and a bolt 12 is passed through the housing 7 and through one of the slots 11 to permit the buffer shank 6 to move inward in the housing 7 against the pressure of the springs 9 within the limitations of the length of the slot 11 in which the bolt 12 is located.

The walls of the pockets 8, except for a side formed by the partitioning wall 10, are substantially cylindrical in form and thus retain the springs 9 in position so that they may function efficiently to yieldingly resist the pressure that may be applied to the buffer member. The chamber of the housing 7 into which the buffer shank 6 extends is substantially rectangular and has a width that is materially greater than the

width of the buffer shank. The buffer shank, however, is provided with two pairs of vertically spaced laterally extending longitudinal flanges 13 that are formed integral with the walls of the buffer shank 6 and may contact with the side walls of the housing 7 near the upper and lower ends of said side walls. The laterally extending flanges reduce the sliding friction along the lateral sides of the buffer shank and prevent freezing when the pressure is at an angle to the axis of the frame of the car as may occur on a curved track. The buffer head or striker plate proper 14 extends across the outer end of the shank 6 and closes the outer ends of the pockets 8. The plate 14 also extends across the outer edge of the housing 7. Thus the plate 14 is reinforced and backed by not only the walls of the pockets 8, but also the flanges 13 with which the plate 14 is formed integral. If the plate 14 should be depressed sufficiently, the marginal edge portion thereof will squarely strike the end edge of the housing 7. The bottom walls of the pockets 8 are also provided with a pair of enlarged portions or skid portions 15 that form sliding contact surfaces of limited, and yet sufficient area, to give the least frictional resistance to the movement of the buffer shank and at the same time have a sufficient cross-sectional area to withstand the downward slap or hammering that might occur in the relative car movements. The housing between the skid portions 15 is raised so that the lower end of the pin 12 will be located above the lower side of the lower chamber wall of the housing and will thus be protected from the shank of the coupler which is located directly below the housing. The upper wall of the striker plate member has a plain surface 16 that extends above and somewhat beyond the centers of the pockets which gives a large area to engage the inner upper surface of the housing 7.

The housing 7 is also provided with depending arms 17 that may be channeled or ribbed in order to render the arms 17 sufficiently strong. Each arm 17 may also be reinforced by a bracket like web 18 that is formed integral with the housing and the arm 17. A bolt or rod 19 extends across the ends of the arms, the ends of the bolts being located in vertical slots 20. A sleeve or roller 21 is located on the bolt or rod 19. A coupler member includes a shank or draw bar 22 which is located between the arms 17 and rides upon the sleeve or roller 21. The distance between the arms 17 is greater than the width of the draw bar 22 to allow for a certain amount of lateral play of the coupler to permit the slight angular relation that exists when two adjoining cars are on a curved track. This

lateral movement of the coupler and the in and out movement caused by the change in the draft on the coupler produces some wear on the under side of the coupler draw-bar. This wear can be readily taken up by shims 23 that are located in sockets formed in the ends of the arms 17 so as to raise the sleeve 21 and rod 19 a short distance to correct the wear that may occur in the coupler 22. The sleeve 21 being rotatable on the bar 19 experiences but very little wear, and such wear may also be corrected by the shims 23. Also the bar 19 and the sleeve 21 may be easily replaced if desired.

The matter of connecting the resilient striker plate with the car will vary according to the construction and arrangement of the end sills and the draft sills of the car. In the form of construction shown, the housing is located below the end sill 24 and between the draft sills 25. The particular draft sills shown are made in the form of Z-bars having the flanges 26 and 27. The flanges 27 are located on the top of the housing 7 and the housing is riveted by the rivets 28 that extend through the wall of the housing and the draft sills at different points, as shown. The flanges 13 also provide spaces between the buffer shank 6 and the wall of the housing 7 for the heads of the rivets that may be located in the chamber of the housing in which the buffer shank 6 is located and so that the movement of the buffer shank 6 will not be interfered with by the rivets.

In the form of construction shown in Fig. 5 the buffer shaft 30 is provided with three pockets in which the springs 31 are located. The housing 32 in which the buffer shank 30 telescopes is provided on its inner end wall with suitable projecting lugs or cylindrical flanges 33 for maintaining the springs 31 in position. The housing is provided with slots 34 in which the bolts 35 are located and which extend through vertical openings formed in the buffer shank 30. The bolts 35 thus move with the buffer member. The housing 32 is backed by the end sill 24 in the particular construction shown. This, however, as stated before, may be varied according to the construction of the car, particularly, in the vicinity of the coupler.

Thus the resilient striker plate assembly supports the coupler in juxtaposed relation therewith and so that the coupling head 36 will strike the center portion of the striker plate 14 and force the striker plate member against the compression springs 9 in the form shown in Figs. 1 to 4 and 31 in the form shown in Fig. 5. These springs will then coact with the coupling spring to resist further inward movements of the buffer member and the draw bar 22. The position of the striker plate 14 or of the striker plate 30 is such as to allow a certain amount of

movement of the coupling that is resisted by the coupling spring until the coupling head strikes the striker plate when the springs of the resilient striker plate assembly which have a much greater yielding resistance, contact with the coupling spring to oppose the pressure that the coupling head is subjected to, the springs of the resilient striker plate assembly being designed to completely over-
come the extreme pressures, with a proper margin of safety, that may occur at this point and within the limitations of movements of the end of the coupler to properly protect the draw bar spring and prevent impact of the end of the coupler directly or indirectly against the supporting structure of the car.

I claim:

In a buffer attachment for railway cars, a housing attachable to the underframe of a railway car at an end of the latter, said housing having a chamber open at the outer

end of said housing, a buffer having a shank extending slidably into said chamber of the housing and having a plate-like head at the outer end of the shank, spring means between said shank and the inner end wall of said chamber of the housing, a pair of transversely spaced integral arms depending from said housing, the lower end portions of said arms having aligned vertical slots, a rod having its end portions adjustably supported in said slots, said rod being capable of bodily movement in a vertical plane for the full height of said slots and a roller on said rod between said arms for supporting the draw bar of the draft gear of the railway car so that a given inward movement of the coupler head at the outer end of the draw bar will cause a portion of said coupler head to strike said buffer head.

In testimony whereof, I have hereunto signed my name to this specification.

CHARLES E. WICKERSHAM.
